UNITED STATES PATENT OFFICE.

KENNETH A. MOWAT, OF ATKINS, MICHIGAN.

BED.

1,325,488.

Specification of Letters Patent. Patented Dec. 16, 1919.

Application filed April 12, 1919. Serial No. 289,761.

To all whom it may concern:

Be it known that I, KENNETH A. MOWAT, a subject of the King of Great Britain, residing at Atkins, in the county of St. Clair 5 and State of Michigan, have invented new and useful Improvements in Beds, of which the following is a specification.

This invention has reference to beds or couches.

10 The object of the invention is to arrange, in a novel manner, upon a suitable support, such as a bath tub, sections of a bed or couch having means whereby the said sections may be brought to horizontal alignment over the support and sustained in such condition to provide a bed or couch, the said means also permitting the sections to be folded over each other to one side of the support, so that the bath tub may be used 20 for ordinary purposes.

It is a further object of the invention to produce a bed or couch comprising hingedly connected sections suitably supported upon a stationary member, such as a bath tub and 25 which may be arranged to rest one upon the tub and the other along the side of the tub, thus concealing the tub, the said sections also having means whereby the same may be brought in horizontal alignment and supported in such condition to provide a bed and still furthermore the sections being so associated as to permit of the same being folded one over the other alongside of the support without detaching the same from 30 the support, so that free access may be had to the supporting tub.

A further object of the invention is to provide a support, such as an ordinary bath tub with means whereby the same may be 40 readily converted into a bed or couch, such means being detachably associated with the tub; but which, if desired, may remain a permanent fixture therewith.

Other objects and advantages will present themselves as the nature of the invention is better understood, reference being had to the accompanying drawings, in which;

Figure 1 is a transverse sectional view 50 through a support in the nature of a bath tub illustrating the application of the improvement thereon, the device being in its folded and what may be termed inoperative position.

Fig. 2 is a similar view showing the arrangement of parts when the device is set up as a couch or settee.

Fig. 3 is a similar view showing the device set up as a bed.

Fig. 4 is a top plan view of the device as 60 illustrated in Fig. 3.

Fig. 5 is a detail view illustrating the manner in which the legs upon the outer bed section are sustained in supporting position.

Fig. 6 is a greatly enlarged sectional view 65 through the clamping members that engage with the rim or roll of the bath tub.

Fig. 7 is a perspective view of the members constituting the clamp.

Fig. 8 is a perspective view of one of the yieldable brackets carried by the bed section which is arranged over the supporting tub.

Fig. 9 is a detail perspective view looking 75 toward the end of the improvement.

Where extra sleeping space is required I have found that an ordinary bath tub may be converted into a comfortable bed or couch in an easy and comparatively inexpensive manner. In addition to this my improvement may be employed as a settee or couch and when in such position fully encloses the bath tub upon which it is supported, while when the bath tub is required 80 for use the improvement may be folded against one side thereof, occupying small space and offering no inconvenience to the user of the tub. It should, however, in this connection be stated that while the improvement is primarily devised for use in connection with the bath tub, other supporting means may be employed therefor.

Referring now to the drawings in detail, the numeral 1 designates an ordinary construction of bath tub having its edges provided with the usual rolled rims.

In carrying out my invention I employ a strip 3 which is of a length equal to or slightly greater than that of the tub or support 1. This strip 3, at desired intervals is provided with clamping means for securing the same to one of the longitudinal rolls or beads 2 upon the outer face of the tub 1. The clamping means include an inner series 105 of jaws 4 and an outer series of co-acting jaws 5. Each of the jaws is constructed from a suitable plate, preferably of metal

having inner or lower straight portions and outer curved portions, the latter being designated for distinction by the numeral 6. The rounded or curved portions 6 of the jaws 4 are designed to be arranged in contacting engagement with the outer surface of the rim 2, while the rounded surfaces 6 of the jaws 5 are designed to engage with the inner surfaces of the said rim. The jaws 4, at the 10 lower and straight portions thereof are provided with spaced openings through which pass securing elements in the nature of screws 7 that secure the said jaws to the strip 3. Between the screw holes the 15 straight portion of each of the jaws 4 is provided with a round opening, and the lower edge of each of the jaws 4 is outturned providing a straight flange 9, the same having a slot 10 therethrough. Each of the jaws 5 has 20 its lower end formed with a reduced tongue 11 that is designed to pass through the slot 10 in the flange 9 of the respective jaw members 4. Each of the jaw members 5, above the tongue 11 has a round opening 12 designed to register with the opening 8 of the 25 jaw 4 and with openings 13 in the strip 3. Through these registering openings pass the shanks of threaded bolts 14 which are engaged by wing nuts 15, the said wing nuts 30 preferably contacting with washers 16 arranged on the bolts 14 and on the outer face of the strip 3. By this means it will be noted that the jaws 5 may be brought toward the jaws 4 to tightly clamp the rim 2 between the jaws and thus effectively support 35 the strip 3 on the bath tub. By virtue of the curved or rounded outer portions of the jaws 4 and 5 the strip 3 is tightly held upon the supporting tub and can not be removed 40 therefrom until the wing nuts 15 are loosened on the screws 14.

The strip 3, at the ends thereof is provided with headed studs 17 that pass through elongated slots 18 in strap members 19. The 45 straps 19 are preferably of metal and have their outer or free ends pivotally secured, as at 20 to the end portions 21 of a substantially rectangular frame 22 that provides one of the sections of the improvement. The 50 frame 22 has secured therein suitable springs 23 that support a mattress 24, and the said frame, upon what may be termed its inner surface is provided with spring brackets 25 having lower arched portions or feet 26, and 55 these portions 26 are designed to rest on the outer surface of the longitudinal rims of the tub 1, when this section of the device, indicated for distinction by the numeral 27 is arranged over the tub.

60 The second section of the improvement is indicated broadly by the numeral 28 and has its inner side member connected, at spaced intervals to the strip 3 by hinges 29. The section 28 is also provided with springs 30 65 that support thereon a mattress 31, and piv-

totally connected, as at 32 to the outer longitudinal member or side of the frame 28 are legs 33. These legs are designed to be swung inward of the frame when in inoperative or non-supporting position and outward of the 70 said frame when in supporting position. On each of the legs 33 is an offset spring stop member 34 designed, when the legs are swung to supporting position to underlie and contact with the outer side of the frame 75 28, whereby to sustain the said legs against accidental collapse.

The frames are designed to have arranged thereover a suitable covering 35 which wholly incloses the tub 1.

It will be apparent that by arranging the section 27 over the tub and the section 28 in horizontal alinement with the section 27, the device may be set up as a bed, the legs 33, of course, being brought to position to 85 support the section 28. When the device is to be employed as a settee or couch the legs 33 of the section 28 are folded against the said section and the said section swung upon its hinges 29 to a vertical position against 90 the outer face of the strip 3. When the tub is desired for use the section 28 is arranged in the position just mentioned and the section 27 is swung over the tub against the outer face of the section 28, this being 95 permitted by the elongated slots 18 in the straps 19 which hingedly connect the sections 28 with the supporting strip 3.

It is believed, from the foregoing description, when taken in connection with the 100 drawings, the simplicity of the construction and the advantages thereof will be readily apparent to those skilled in the art to which such inventions relate without further detailed description.

Having thus described the invention, what is claimed as new, is:—

1. In combination with a support, of a strip, clamping means carried by the strip for removably connecting the same to the support, frame sections hingedly connected to the strip, one of which is designed to be arranged over and to rest upon the support, and pivoted leg members upon the other section designed when in supporting 110 position to retain both of the sections in horizontal alinement.

2. In combination with a stationary support, of a strip designed to be arranged upon one side of the support, clamping means carried by the strip whereby to secure the same to the support at the upper edge thereof, two frames one of which is hingedly secured to the upper edge of the strip and the other has a loose hinge connection with the ends of the strip, said last mentioned frame designed, when in one position to be arranged over the support, pivoted legs upon the second frame member designed to support the latter in horizontal alinement with the first 120 125 130

mentioned frame when in supporting position and when in non-supporting position to permit the second mentioned frame to be swung against the outer side of the strip 5 and the side of the support, and the hinge connection between the strip and the first mentioned frame permitting said frame to be swung against the second mentioned frame when the latter is in its last mentioned

10 position.

3. In combination with a stationary support, of a strip having clamping means for sustaining the same upon one of the edges of the support, two frames, one of which has 15 a loose strap connection with the ends of the strip and said frame designed, when in one position to overlie the support, depending brackets on said frame having foot portions which rest upon the support, the second 20 frame being hingedly secured to the outer edge of the strip, pivoted legs on said second frame designed, when in supporting position to retain said second mentioned frame in horizontal alignment with the first-mentioned 25 frame and when in folded position to permit of the second mentioned frame being swung against the outer side of the strip, and stop

means carried by the legs for supporting the same in set up position.

4. In combination with a bath tub having 30 a rolled edge providing a rim, of a strip arranged against the rim at one side of the tub, clamping means on the strip including inner spaced jaws and outer jaws loosely connected to the fixed jaws, each of said jaws having 35 their outer portions rounded to engage with the rolled rim of the tub, binding means between the jaws, two frames, straps pivotally secured to one of the frames at the ends thereof and said straps having their free 40 ends slotted, headed studs received in the slots at the ends of the strip, brackets on said frame having curved spring foot portions designed to rest on the rim of the tub, when the said frame is arranged over the 45 tub, the second frame being hingedly secured to the upper edge of the strip, pivoted legs upon the outer side of the second mentioned frame, and spring stop members upon said legs designed to co-engage with the 50 frame for sustaining said legs in supporting position.

In testimony whereof I affix my signature.
KENNETH A. MOWAT.
